Patented Oct. 28, 1919.

UNITED STATES PATENT OFFICE.

RICHARD VARLEY, OF ENGLEWOOD, NEW JERSEY.

ELECTRICAL SWITCH.

1,319,979.

Specification of Letters Patent. Patented Oct. 28, 1919.

Application filed November 21, 1917. Serial No. 203,069.

To all whom it may concern:

Be it known that I, RICHARD VARLEY, a citizen of the United States of America, residing at Englewood, in the county of Bergen and State of New Jersey, have invented new and useful Improvements in Electrical Switches, of which the following is a full, clear, and exact description, reference being had to the accompanying drawings, which form part of this specification.

This invention is a distributor switch which may form part of an ignition system for internal combustion engines. The essential elements of such a distributor (whether operated by the usual "half-time" shaft or forming part of a magneto electric machine) comprise a revoluble arm or flier driven by a shaft, and a plurality of relatively fixed contacts or segments concentrically arranged with respect to the axis of the shaft and symmetrically spaced from one another and mounted or embedded in an insulating support or housing piece flush with a surface thereof over which a contact or brush of the fiber travels. Each contact is electrically connected to a spark plug of a cylinder of the engine. The brush connects with the source of energy which is under control of means including a make and break device or breaker that intermittently opens and closes a circuit to effect delivery of sparking energy to the brush as it successively traverses the contacts or segments.

It has been observed that passage of the brush from contact to contact is attended with or sets up not only local sparking, the effect of which through repetition or "electrical tracking" is to carbonize the surface insulation between contacts, but the deposition of minute particles of metal along said surface. This track, whether formed electrically or mechanically or through the action of both agencies, constitutes a conducting path along which there takes place from the brush divergence or creepage of current to such degree as to defeat in a measure the insular separation or surface insulation of the contacts and cause preignition of the charge of a cylinder respective to a next succeeding contact and under partial compression or cause objectionable disturbance in the ignition circuits.

The object of my invention is to overcome in switch means of the character indicated preignition or other disturbances in the ignition circuits through sparking or current

creepage due to electrical or mechanical tracking, and to accomplish this result without making radical structural changes in the usual mechanism.

60

I shall now describe my invention so that others skilled in the art to which it appertains may understand and construct the same, it being premised, however, that changes may be made within the scope of 65 the appended claims.

Figure 1 is a vertical sectional view of an electrical distributor, embodying my invention; Fig. 2 is a horizontal sectional view on the line 2—2 of Fig. 1; Fig. 3 is a transverse sectional view on the line 3—3 of Fig. 2; Fig. 4 is a fragmentary vertical sectional view of a modified form of my invention; and Fig. 5 is a fragmentary view, corresponding with Fig. 2, of said modified form.

70

The distributor shown is typical in so far as concerns its general construction; the revoluble flier switch arm 2 is driven by a shaft 3 and housed in the casing 4 and provided with a contact brush 5 held pressed against the lower surface 6 along which it travels upon revoluble driving of the arm, for successive contactual engagement of the symmetrically spaced relatively fixed contacts or segments 7 embedded in the top 75 piece 8 of the casing 4 and having their terminal extensions therethrough flush with the surface 6 and concentrically disposed with respect to the axis of the shaft 3, in the annular recess or groove 9 and in 80 the path of travel of the brush 5. As will be clearly understood by those skilled in the art, the flier brush 5 connects with a source of ignition current through the central terminal 10 and contact spring or plate 10^a, 85 and the contacts 7 connect, through suitable terminals 7^a and conductors (not shown) with the spark plugs in the cylinders of the engine. The body or housing 4 may be formed of rubber, bakelite or other suitable 90 material and its surface or surfaces 6 may be formed by the lower face or faces of a separate ring 11 of rubber or other suitable material, having the annular recess 9, the ring being embedded or molded or otherwise fastened in the piece 8.

95

Instead of a track formed of two concentric portions or recessed, as described, I may employ a single track, as shown in Figs. 4 and 5. In this construction the flier brush 110 5 projects beyond the track 6' to such extent as to traverse upon rotation of the flier.

the fixed contacts spaced upon the track 6' and the terminals of which are flush with the surface of the track.

By mounting the contacts in the manner 5 above described, so as to be spaced from the surfaces 6, I overcome the tendency to formation of an electrical or mechanical track. As will be seen, the brush 5 is so supported by the track or tracks that it slides along 10 the surfaces 6 or 6' without canting and therefore without mechanical interference from the contacts.

Having described my invention, what I claim is:

15 1. In a distributor, a contact brush, a body member having a continuous circular track for the contact brush, and a counter surface, and contacts projecting from said surface, and having terminals substantially 20 flush with the track.

2. In a distributor, a body member having a continuous circular track for a movable contact brush, and a counter surface, contacts mounted in the body and projecting

from said surface, and having terminals 25 substantially flush with the track, and a flier having a contact brush, said track being so arranged as to prevent canting of the brush.

3. In a distributor, a body member having 30 a surface provided with a raised circular portion, and a brush adapted to travel along and supported by the portion against canting and a plurality of contacts projecting from the surface and spaced from the portion 35 and having terminals substantially flush with the surface of said portion, over which the brush travels.

4. In a distributor, a body member having a circular path over which a contact brush 40 moves, and an annular counter recess, contacts mounted in the body and having terminals disposed in the recess and substantially flush with the path, and a flier having a contact brush. 45

In testimony whereof I have hereunto set my hand.

RICHARD VARLEY.
